MOTOR CONTROL SYSTEM

George E. King, Williamsville, N. Y., assignor to
Westinghouse Electric Corporation, East Pittsburgh, Pa., a corporation of Pennsylvania

Application November 26, 1948, Serial No. 62,212

3 Claims. (Cl. 318—282)

1

This invention relates generally to control systems for an electric motor and, more particularly, to a control system embodying automatic operation of a driving motor to effect reciprocation of a machine tool element, such as a planer platen. It should be understood, however, that the present control system is likewise useful for other reciprocating devices such as machine tools for effecting relative movement between a work piece and tool while the tool performs its cutting or other deforming operation, for example, draw-cut and push-cut shapers, roll grinders, transfer tables and the like, and generally wherever an adjustable or variable is supplied to the motor.

Heretofore, in the operation of reciprocating machine tools, such as, for example, planers, great difficulty has been experienced in attempts to obtain quick short stroke operation, such as cut strokes of seventy or more per minute, due to the appreciable transfer time required for operation of the reversing relays.

It has been proposed to electrically interlock the coils of the reversing relays, that is, the so-called "cut" and "return" relays, which relays are effective to cause the motor to drive in the cut and return directions, respectively, when energized. Such scheme includes normally closed interlocking contacts in series with the respective relay coils to prevent energization of both coils when both reversing limit switches are in the normally closed position. Thus when the planer platen moves in the cut direction, then near the end of the cut stroke, the dog strikes the "cut" limit switch and deenergizes the "cut" relay, causing it to drop out. A normally closed interlock on the "cut" relay will effect energization of the "return" relay coil through the "return" limit switch and the "return" relay will close. However, before the "return" relay can pick up, the "cut" relay must drop out. Likewise, in the operation of the planer platen in going from the return to the cut direction, the "return" relay must drop out before the "cut" relay can pick up. This considerably retards the speed of reversal of the motor and limits the number of cut strokes obtainable per minute since it is necessary to wait for complete dropping out of one reversing relay before the other one can begin to pick up.

An object of the present invention is to provide a control system for controlling the relative reciprocating movement between a tool and work piece in a planer or other reciprocating device, which control system will allow rapid

2

reversal of the driving motor from full selected speed in one direction to full selected speed in the opposite direction so that a very small portion of the total time required to complete one operating cycle will be used in the reversing operation.

A further object of this invention is to provide a quick yet smooth reversal of a driving motor of a reciprocating machine tool, such as a planer, so as to eliminate any undue strain on the gears of the machine so that cut strokes upwards of seventy per minute are readily obtainable.

A more specific object of this invention is to provide a motor control system for driving a planer platen or other reciprocating machine tool part, which control system includes a pair of reversing relays which are sequentially operated to effect reversal of the drive of the platen, each of which relays includes normally closed contacts and normally open contacts so that when a dog hits a limit switch, either near the end of the cut, or near the end of the return stroke, the normally closed contacts will open to deenergize the particular relay, causing drive in a given direction, and the normally open contacts will close to complete an energizing circuit for the other relay to effect reversal of the direction of drive, so that as one relay is dropping out, the other will be picking up, therefore considerably shortening the transfer time required for operation of the relays to cause reversal of the drive.

Other objects and advantages not specifically hereinbefore recited will become more apparent from a study of the following specification when considered in conjunction with the accompanying drawing in which:

Fig. 1 is a diagrammatic representation, in the form of a wiring diagram, of a complete control system, in accordance with my invention, for a reversing motor for operating a planer platen or other reciprocating mechanism, and

Fig. 2 is an elevational view, somewhat diagrammatic, of a planer having a platen which is reciprocated by the control system shown in Fig. 1.

Referring more particularly to the drawing, a direct current motor M is mechanically coupled to drive a machine tool element, such as a planer platen 1, as shown in Fig. 2, mounted on a support or base 2 and which platen is mounted on suitable guideways to reciprocate in a horizontal direction thereon. A generator G is provided having its armature 3 connected

in series with a generator series field winding 4, and with armature 5, of the motor M. The generator G is provided with separately excited field windings 6 and 7 wound in opposite directions so that energization of one winding will cause current flow through the generator-motor armature circuit in one direction to effect operation of the motor in one direction, and energization of the other winding will reverse the current flow in this circuit and effect operation of the motor in reverse direction. A separately excited motor field winding 8 is provided for motor M, which field winding is connected across line terminals L1 and L2. The line terminals L1 and L2 are energized by means of an exciter E including an exciter armature 9, a shunt field winding 10, a variable shunt resistor 11 and a series field winding 12. The exciter is operated at constant speed from a suitable prime mover, and in a well known manner, supplies a constant potential to the line terminals L1 and L2. Both the generator G and exciter E may be mechanically coupled to, and driven by a motor (not shown), such as, for example, an alternating current motor or other prime mover.

Referring to Fig. 2 of the drawing, as motor M drives platen 1 in the cut direction, that is, to the left as viewed in the drawing, a dog 13 which is fixed thereto will move therewith and, near the end of the cut stroke, will operate a "cut" limit switch 14 so as to effect reversal of the driving motor and movement of the platen in the return direction. Likewise, when the dog 15, which is secured to the platen 1, strikes the "return" limit switch 16 near the end of the return stroke, it will cause deenergization of the "return" relay and initiate reversal of the motor so as to cause drive in the cut direction as will be described in detail hereinafter.

Automatic cut operation

More specifically, and referring to Fig. 1 of the drawing, assume that it is desired to initiate operation of the motor in the cut direction.

"Automatic cut" pushbutton switch 17 is temporarily depressed, thereby closing its contacts 18, which will complete a temporary energizing circuit through coil C of the "cut" relay 19. This circuit may be traced from terminal L1, through conductor 20, contacts 18, the normally closed contacts 21 of the "automatic return" pushbutton switch 22, normally closed upper contacts 23 of the "cut limit" switch 14, relay coil C, conductor 25 to terminal L2.

As the relay 19 picks up the contacts 26 and 33 are closed and the contacts 62 are opened. The closing of contacts 26 establishes an energizing circuit for the field winding 6. This circuit may be traced from lead L1 through the resistor 27, contacts 69, field winding 6, contacts 26 and conductor 25 to the lead L2. The left-hand half of resistor 31 provides a shunt for field 6. The resistance value of resistor 31 is so chosen as not to affect normal operation but yet provides a suitable discharge path for the field. Since the contacts 69 shunt the rheostat 28, the field 6 is heavily energized to provide for a rapid building up of the voltage of the generator G to a higher than normal value to thus provide a heavy starting torque for the motor M.

The opening of contacts 62 prevents energization of the generator field suicide contactor 71.

Picking up of relay 19 will also effect energization of coil AR of the relay 39 having a small inherent time delay to assure the above men-

tioned heavy starting torque. The circuit for coil AR may be traced from terminal L1, through conductor 20, contacts 18, conductor 32, contacts 33 of the "cut" relay 19, conductors 34 and 35, "stop" pushbutton contacts 36, coil AR, conductor 37 to terminal L2. Energization of coil AR will effect closing of its contacts 38 which will complete a sealing circuit to maintain the relay 39 in the energized position, which circuit may be traced from terminal L1, through conductor 40, contacts 38, conductors 41 and 35, "stop" pushbutton contacts 39, coil AR, conductor 37 to terminal L2. Coil AR will therefore seal itself in so long as the "stop" pushbutton is not depressed, and as will appear hereinafter, its contacts 38 complete a circuit through either of the reversing relay coils C or R, depending on the direction of drive of the motor. As relay 39 picks up, its contacts 69 and 70 open to remove the shunt circuits for the rheostats 28 and 45—also, its contacts 61 open. A sealing circuit for coil C will thus be completed which may be traced from line terminal L1 to conductor 42, contacts 38, conductors 41, 35 and 34, contacts 33, conductor 32, contacts 21 and 23, coil C, conductor 25 to terminal L2. Hence, even after release of the "automatic cut" pushbutton switch 17, coil C will remain energized.

After contacts 26 are closed and contacts 69 are opened by the operation of relay 39, a new energizing circuit is established for the generator field winding 6. This circuit may be traced from line terminal L1, through resistor 27, rheostat 28, conductor 29, generator field winding 6, conductor 30, contacts 26, conductor 25 to terminal L2. A shunt path is also provided through the left hand portion of resistor 31. Energization of the generator field winding 6 through rheostat 28 will cause the normal automatic cut operation voltage on the generator and in consequence the motor M will operate at its normal automatic cut speed.

The motor will continue to drive in the cut direction until near the end of the cut stroke, the dog 13 will hit the "cut" limit switch 14, thereby opening its normally closed contacts 23 and closing its normally open contacts 42. Opening of contacts 23 will effect deenergization of coil C, thereby opening contacts 26 and deenergizing generator field winding 6. Closing of contacts 42 will complete an energizing circuit through coil R to effect operation of the "return" relay 43. The circuit through coil R may be traced from terminal L1, through conductor 40, contacts 38, conductors 41 and 35, contacts 42, conductor 49, contacts 50 and 51, conductor 52, relay coil R, conductor 25 to terminal L2. Upon energization of coil R, contacts 44 close to complete a circuit through shunt field winding 7 which may be traced from terminal L1 through resistors 27 and rheostat 45, conductor 46, field winding 7, conductor 47, contacts 44, conductor 25 to terminal L2. A shunt path is also provided through the right half of resistor 31. Since field winding 7 is wound oppositely to field winding 6, there will circulate current through the armatures of the generator and motor in an opposite direction so as to effect reverse operation of the motor M and movement of the planer platen 1 in the return direction. In other words, while the "cut" relay 19 is dropping out, field winding 6 is deenergized and field winding 7 is energized.

As coil R is energized, relay 43 picks up and its

contacts 53 close to complete a sealing circuit through coil R which may be traced from line terminal L1 through conductor 40, contacts 38, conductors 41, 35 and 34, contacts 53, conductors 60, contacts 50 and 51, conductor 52, relay coil R, conductor 25 to terminal L2. Thus the motor will operate in the return direction.

Near the end of the return stroke, dog 15 will hit the "return" limit switch 16 so as to open its lower contacts 51 to cause deenergization of relay coil R and will close its upper contacts 56 to complete an energizing circuit for relay coil C. This circuit may be traced from line terminal L1, through conductor 40, contacts 38, conductors 41, 35 and 57, contacts 56, contacts 21 and 23, coil C, conductor 25 to terminal L2. Energization of coil C will complete a circuit through field winding 6 to cause drive of the motor in the cut direction as described above. At the end of the cut stroke, dog 13 hits the "cut" limit switch 14 and the cycle is repeated.

While the actual sequence of operation is such that contacts 23 open slightly sooner than contacts 42 close, no harm would result if windings 6 and 7 were simultaneously connected to the leads L1 and L2.

It is one of the outstanding advantages of this invention that the second field winding, as field winding 7, of the main generator for effecting the reverse operation of the motor connected to the generator is energized at substantially the very instant the generator field, caused by the first field winding, as field winding 6, is decaying. The field reversal is thus expedited in the extreme. It is thus apparent that there is no delay at the ends of the planer platen strokes, with the result that many more strokes per unit of time are obtained than with prior art controls.

Automatic return operation

When it is desired to initiate drive of the motor in the return direction to obtain automatic return operation, the "automatic return" pushbutton switch 22 is temporarily depressed, thereby opening contacts 21 which effect deenergization of coil C and of field winding 6 and closing of contacts 58 which completes an energizing circuit through coil R which may be traced from terminal L1 through conductor 59, contacts 58, conductor 49, contacts 50 and 51, conductor 52, relay coil R, conductor 25 to terminal L2.

As the relay 43 picks up the contacts 44 and 53 are closed and contacts 63 are opened. The closing of contacts 44 establishes an energizing circuit for the field winding 7. This circuit may be traced from terminal L1 through the resistor 45, contacts 70, field winding 7, contacts 44 and conductor 25 to the lead L2. The right-hand half of resistor 31 provides a shunt for the field 7. The resistance value of resistor 31 is so chosen to provide for normal operation but yet to provide a suitable discharge path for the field 7. Since the contacts 70 shunt the rheostat 45, the field is heavily energized to provide for a rapid building up of the voltage of the generator G to a higher than normal value to thus provide a heavy return starting torque for the motor M.

The opening of contacts 63 prevents energization of the generator field suicide contactor 71.

Picking up of relay 43 also effects energization of coil AR of relay 39. This relay 39 has a small inherent time delay to assure the above-mentioned heavy return starting torque. The circuit for coil AR may be traced from lead L1, through conductor 59, contacts 58, conductors

49 and 60, contacts 53, conductors 34 and 35, stop button 36, coil AR, and conductor 37 to lead L2. Energization of coil AR will effect closing of its own contacts 38 to establish its hold-in circuit. A sealing circuit for coil R is thus established, which circuit may be traced from lead L1 through conductor 40, contacts 38, conductors 41, 35 and 34, contacts 53, conductors 60 and 49, contacts 50 and 51, conductor 52, coil R, and conductor 25 to the terminal, or lead, L2. Hence, relay 43 remains energized even though push button 22 is released.

After contacts 44 are closed and contacts 70 are opened by the operation of relay 39 the field 7 is energized through rheostat 45 so that normal automatic return operation voltage is provided by the generator G, and in consequence the motor M will operate at its normal return speed.

Near the end of the return stroke, dog 15 hits the "return" limit switch 16, opening its contacts 51 so as to deenergize relay coil R and closing its contacts 56 to complete a circuit through coil C which may be traced from line L1, through conductor 40, contacts 38, conductors 41, 35 and 57, contacts 56, 21 and 23, coil C, conductor 25 to line terminal L2. A holding circuit will be completed for coil C through its central contacts 33, which circuit may be traced from conductor L1 through conductor 40, contacts 38, conductors 41, 35 and 34, contacts 33, conductor 32, contacts 21 and 23, coil C, conductor 25 to terminal L2. Contacts 44 of relay 43 will therefore complete an energizing circuit through coil 7. The motor M will therefore drive in the return direction until the cut limit switch is hit by dog 13, upon which the cycle will be repeated.

Stoppage of motor drive

To stop the machine, the "stop" pushbutton is depressed, opening contacts 36 which will deenergize coil AR, thereby opening contacts 38 which will effect deenergization of either coil C or coil R, depending upon the direction of movement of the planer—it being remembered that the holding circuits for both coils C and R extend through contacts 38. As relay 39 drops out, contacts 61 close, and since relays 19 and 43 have both dropped out, contacts 62 and 63 also will close. As soon as the voltage across the armature of the generator and motor falls below a predetermined value (inasmuch as both generator field windings 6 and 7 are deenergized), coil DCR will become sufficiently deenergized as to cause its relay 64 to drop out, thereby closing contacts 65 and completing an energizing circuit through coil DFR which may be traced from line L1, through contacts 64, 62, 63 and 65, coil DFR to line terminal L2. Upon energization of coil DFR, contacts 67 close, which will effect insertion of a generator shunt field winding 68 which is wound oppositely to the series field winding 4 so as to have a neutralizing or bucking effect on field winding 4 and thereby bring the driving motor rapidly to a standstill. The dropping out of relay 39 also effects closure of contacts 69 and 70 effecting bridging of the field rheostats 23 and 45 so as to prepare the circuit for a subsequent starting operation.

Thus it will be seen that I have provided a highly efficient control circuit embodying quick acting reversing relays, whose operating or transfer time is reduced to a minimum, for effecting rapid reversal of the direction of drive of a driving motor, which in turn effects rapid reciprocating movements of a planer platen or other reciprocating

ing element. This allows a large number of cut strokes per minute, that is, in excess of seventy, which would be difficult or impossible if conventional relay circuits were used instead.

While the control system embodying the principles of my invention has been described in connection with the operation of a planer platen, it will be understood, of course, that it is likewise useful to effect relative reciprocating movement between a cutting or deforming element of any other machine tool and a work piece, irrespective of which is held stationary while the other is reciprocated—or, in fact, any reciprocating device.

While I have illustrated and described a certain specific embodiment of my invention, it will be understood that this is by way of illustration only, and that various changes and modifications may be made within the contemplation of my invention and within the scope of the following claims.

I claim as my invention:

1. A control system for a reciprocating planer platen provided with dogs for actuating certain limit switches constituting part of the control system, in combination, a reversible electric motor for driving said platen, said motor including an armature and a field winding, a generator including an armature and a pair of oppositely wound field windings, means, including electrical control apparatus, for energizing said motor and generator field windings, said control apparatus including a pair of reversing relay contactors, each of which upon energization is adapted to complete an energizing circuit through one of said generator field windings, a limit switch associated with each of said relay contactors and one adapted to be operated, by one dog on the planer platen, near the end of its movement in a given direction and the other adapted to be operated, by the other dog on the planer platen, near the end of its movement in the opposite direction, each of said limit switches including normally closed contacts in series with the coil of its associated contactor and normally open contacts which when closed are adapted to complete an energizing circuit through the coil of the other contactor, so that as one of said contactors drops out the other will immediately pick up, thereby considerably decreasing the transfer time required for operation of said contactors, one of said contactors including normally open contacts which when closed completes an energizing circuit through one of said generator field windings and the other of said contactors including normally open contacts which when closed completes an energizing circuit through the other of said generator field windings to that as said contactors operate in succession, the direction of drive of said motor is reversed so as to reverse the direction of movement of said planer platen.

2. A control system for a reciprocating planer platen provided with dogs for actuating certain limit switches constituting part of the control system, in combination, a reversible electric motor for driving said platen, said motor including an armature and a field winding, a generator including an armature and a pair of oppositely wound field windings, means, including electrical control apparatus, for energizing said motor and generator field windings, said control apparatus including a pair of reversing relay contactors, each of which upon energization is adapted to complete an energizing circuit through one of said generator field windings, a limit switch associated with each of said relay contactors and one adapted to be operated, by one dog on the

planer platen, near the end of its movement in a given direction and the other adapted to be operated, by the other dog on the planer platen, near the end of its movement in the opposite direction, each of said limit switches including normally closed contacts in series with the coil of its associated contactor and normally open contacts which when closed are adapted to complete an energizing circuit through the coil of the other contactor, so that as one of said contactors drops out the other will immediately pick up, thereby considerably decreasing the transfer time required for operation of said contactors, one of said contactors including normally open contacts which when closed complete an energizing circuit through one of said generator field windings and the other of said contactors including normally open contacts which when closed complete an energizing circuit through the other generator field windings so that as said contactors operate in succession, the direction of drive of said motor is reversed so as to reverse the direction of movement of said planer platen, a manually operable pushbutton

20 in succession, the direction of drive of said motor is reversed so as to reverse the direction of movement of said planer platen, a manually operable pushbutton associated with each relay contactor 25 in a manner so that temporary depression of the pushbutton will temporarily energize the associated contactor coil, a pair of hold-in circuits for maintaining each of said coils in an energized condition after release of the associated pushbutton, a contactor having contacts which are common to both said holding circuits and including an energizing coil, and a stop pushbutton switch in series with said last mentioned coil so that upon depression it will cause opening of said 30 last mentioned contacts, deenergizing both of said holding circuits.

3. A control system for a reciprocating planer platen provided with dogs for actuating certain limit switches constituting part of the control system, in combination, a reversible electric motor 40 for driving said platen, said motor including an armature and a field winding, a generator including an armature and a pair of oppositely wound field windings, means, including electrical control apparatus, for energizing said motor and generator field windings, said control apparatus including a pair of reversing relay contactors, each of which upon energization is adapted to complete an energizing circuit through one of said generator field windings, a limit switch associated with each of said relay contactors and one adapted to be operated, by one dog on the planer platen, near the end of its movement in a given direction and the other adapted to be operated, by the other dog on the planer platen, near the end of its movement in the opposite direction, each of said limit switches including normally closed contacts in series with the coil of its associated contactor and normally open contacts which when closed are adapted to complete an energizing circuit through the coil of the other contactor, so that as one of said contactors drops out the other will immediately pick up, thereby considerably decreasing the transfer time required for operation of said contactors, one of said contactors including normally open contacts which when closed complete an energizing circuit through one of said generator field windings and the other of said contactors including normally open contacts which when closed complete an energizing circuit through the other generator field windings so that as said contactors operate in succession, the direction of drive of said motor is reversed so as to reverse the direction of movement of said planer platen, a manually operable pushbutton

associated with each relay contactor in a manner so that temporary depression of the pushbutton will temporarily energize the associated contactor coil, a pair of hold-in circuits for maintaining each of said coils in an energized condition after release of the associated pushbutton, a contactor having contacts which are common to both said holding circuits and including an energizing coil, and a stop pushbutton switch in series with said last mentioned coil so that upon depression it will cause opening of said last mentioned contacts, deenergizing both of said holding circuits, said reversing relay contactors including contacts which are in series with the associated holding circuit for the particular relay contactor coil and the circuit relationship with one of said first

5 mentioned pushbutton switches associated with said relay contactors.
